H. M. BOE.
GREASE AND OIL DISPENSING APPARATUS.
APPLICATION FILED MAR. 12, 1919.

1,369,517.

Patented Feb. 22, 1921.

UNITED STATES PATENT OFFICE.

HANS M. BOE, OF MINNEAPOLIS, MINNESOTA.

GREASE AND OIL DISPENSING APPARATUS.

1,369,517.

Specification of Letters Patent. Patented Feb. 22, 1921.

Application filed March 12, 1919. Serial No. 282,139.

To all whom it may concern:

Be it known that I, HANS M. BOE, a citizen of the United States, resident of Minneapolis, county of Hennepin, State of Minnesota, have invented certain new and useful Improvements in Grease or Oil Dispensing Apparatus, of which the following is a specification.

The object of my invention is to provide an attachment for a grease or oil tank or container by means of which the lubricant can be drawn out of the tank and discharged through a suitable nozzle into a bearing, differential or any other device where the lubricating material is needed.

A further object is to provide an apparatus which will be simple and inexpensive in construction and easily operated.

Other objects of the invention will appear from the following detailed description.

The invention consists generally in various constructions and combinations, all as hereinafter described and particularly pointed out in the claims.

In the accompanying drawings forming part of this specification,

Figure 1 is a side view, partially in section, of a dispensing apparatus with my invention applied thereto,

Fig. 2 is a vertical sectional view through the tank attachment,

Figs. 3 and 4 are detail views, showing the metallic disk for holding the piston cups in place.

In the drawing, 2 represents a tank or container having a leg 3 and caster supports 4 on which the tank is moved conveniently from place to place. 5 is a cover, suitably secured to the top of the tank and provided on one side with a projecting bracket 6 having a vertical socket 7 therein. At the bottom of the tank is an outlet or discharge port 8 leading to a passage 9 which terminates in an elbow 10 into which a nipple 11 is tapped. 12 represents a pump head, connected with the other end of the nipple and containing a chamber 13, the nipple having a seat 14 for a ball valve 15^a which normally rests by gravity on the seat and closes the nipple. A pump barrel 15 is seated on the

top of the pump head 12 and communicates therewith through a passage 16, a pin 17 being mounted in the walls of said head and bridging said passage to prevent the valve 15^a from being drawn up into the barrel on the upstroke of the plunger. A pin 17^a is also provided in the wall of the head 12 to limit the movement of the ball valve 15^a toward the discharge port of the head. A piston rod 18 is mounted in said barrel and has a head 19 at its lower end that is tapped to receive a bolt 20 and piston cups 21 are placed back to back on said bolt and seated against said head, being clamped securely thereon by the tightening of said bolt. These cups are preferably of leather or some other suitable flexible material and their edges are held in contact with the inner walls of the barrel by suitable means, preferably the metallic disks 22, preferably of brass, having radial slits 23 in their edges to form a series of spring-like tongues 24 which, when the edge of the disk is folded, lap one another slightly on one side, as indicated in Fig. 3 and have the function of holding the flexible edges of the cups against the walls of the barrel with a yielding pressure. The disks are made and pressed outwardly on the cups when the clamping bolt is tightened and the disks and cups drawn together.

In making these brass disks, I cut a series of radial slits in the edges thereof and then, when the disk is folded to the form shown in Fig. 4, the abutting edges of the disks will slide by each other, said edges being slightly offset in the act of cutting the slits, so that it is only necessary to fold the disk to the form shown in Fig. 4, when the tongues 24 will assume the position illustrated in Fig. 3. These disks I regard as an important feature of the invention.

Above the barrel 15 is a housing 25 in which a shaft 26 having an operating handle 27 is journaled and a pinion 28 is mounted on said shaft to engage the teeth 29 of the piston rod 18. A hollow guide 30 is provided above the housing 25 forming a continuation of the barrel 15 and consists preferably of a section of pipe inserted into the socket 7 and held rigidly thereby in

line with the barrel to receive the rod 18 when the piston is raised by the movement of the operating crank 27. The plunger rod and its rack are wholly inclosed by the barrel and the hollow guide 30 and are thereby made dirt and dust-proof, and the upper end of the pipe 30, radially mounted in the cover 5, serves as a convenient handle for moving the tank from place to place. By mounting the piston rod in this way I not only thoroughly protect it but avoid the necessity of projecting the rod a considerable distance above the tank, as frequently is done in pump attachments of this kind

15 The head 12 has a port 31 therein communicating with a chamber 32 and provided with a seat 33 for a ball valve 34 which normally rests by gravity on said seat and closes the port. A section of hose 35 is connected 20 with the chamber 32 and is provided with a nozzle 36 and a controlling valve 37. The wall of the chamber 32 is provided with prongs or stops 38 in the path of the ball 34 to arrest movement of the ball when it is 25 raised from its seat by the pressure of the lubricating material and allow such material to flow around the ball into the hose section 35 and from thence to the nozzle and be discharged. This head and its connections 30 are of ordinary pump construction to which I make no claim.

In operation, the crank 27 is revolved to raise the plunger. The valve 15^a is thereby lifted from its seat and a quantity of the 35 lubricating material is drawn from the tank up into the barrel 15, the valve 34 being closed at this time. As soon as the suction of the plunger ceases, the valve 15^a will return to its seat and be forced thereon when 40 the piston begins its downward movement and the lubricating material accumulated in the barrel will flow down through the chamber 13 and up through the port 31 into the chamber 32 and from thence to the nozzle, 45 the rapidity of the discharge depending, of course, upon the speed of descent of the plunger.

During the movement of the plunger the 50 spring disks 22 through their yielding contact with the flexible cups 21, will form a close joint between said cups and the walls of the barrel and insure the piston performing its proper function in the operation of the pump. The amount of lubricant 55 discharged may be approximately determined by the stroke of the pump. I do not, however, rely upon this means for determining the quantity of lubricant discharged, as provision is made in the tank 2 through the 60 medium of a piston in the tank and an indicator on the cover 5 (not shown) through the movement of which the discharge of lubricant from the tank is accurately measured. This piston and indicator form the 65 subject matter of prior applications for

U. S. patents filed by me and I make no claim therefore to these devices in this case and have not thought it necessary to incorporate them in the drawings.

I claim as my invention: 70

1. The combination, with a tank adapted to contain a lubricant and having a discharge passage at its lower end and a pipe connection therefor, of a pump having means at its lower end for communication 75 with said pipe connection and provided with a barrel and piston and rod therein, a pipe forming an upward continuation of said barrel concentric therewith and having a bearing at its upper end on said tank and forming a convenient handle for moving the tank, said pump also having a hose connection and nozzle therefor and suitable valves and means for reciprocating said piston rod and piston in said barrel and pipe 80 to fill and empty said barrel.

2. The combination, with a tank adapted to contain a lubricant and having a discharge port in its bottom, of a pump arranged outside the walls of said tank and 90 adjacent thereto and having a pipe connection at its lower end with said port, a pump barrel mounted on said pipe connection, a hollow guide forming a vertical continuation of said pump barrel and having its 95 upper end rigidly mounted in the top of said tank, a piston in said barrel having a toothed rod slidable in said guide and concealed and protected thereby, a shaft mounted near said barrel and having a pinion engaging the teeth of said rod and an operating crank for said shaft, a hose connected with the lower portion of said pump and having a discharge nozzle and valves for regulating the delivery of the lubricant 100 from said tank to said barrel and to said hose when said piston is reciprocated.

3. The combination, with a portable tank adapted to contain a lubricant and having a discharge passage at its lower end and a pipe connection therefor, of a pump having means at its lower end for communication 110 with said pipe connection and provided with a barrel and piston and rod therein, a guide for said rod forming an upward continuation of said barrel and having a bearing at its upper end on said tank and forming a convenient handle for moving said tank, said pump also having a hose connection and nozzle therefor and suitable valves and 115 means for reciprocating said piston rod and piston in said barrel and guide to fill and empty said barrel.

4. The combination, with a portable tank adapted to contain a lubricant and having a 125 discharge port, of a pump arranged outside the walls of said tank and adjacent thereto and having a pipe connection at its lower end with said port, a pump barrel mounted on said pipe connection, a guide connected 130

with said barrel and secured to the cover of said tank and forming a hand grip for moving said tank, a piston in said barrel having a rod slidable in said guide, a pinion 5 geared to said rod and having an operating crank, a hose connected with the lower portion of said pump and having a discharge

nozzle, and valves for regulating the delivery of the lubricant from said tank to said barrel and to said hose when said piston is 10 reciprocated.

In witness whereof, I have hereunto set my hand this 27th day of February 1919.

HANS M. BOE.
